UNITED STATES PATENT OFFICE.

GEORGE E. BRITTAI, OF BOSTON, MASSACHUSETTS, ASSIGNOR TO IRVING L. KEITH,
OF HAVERHILL, MASSACHUSETTS.

HOLDING DEVICE FOR SOLE-CLAMPING MEANS.

1,250,550.

Specification of Letters Patent. Patented Dec. 18, 1917.

Application filed March 8, 1915. Serial No. 12,804.

To all whom it may concern:

Be it known that I, GEORGE E. BRITTAI, a citizen of the United States, residing at Boston, in the county of Suffolk, in the State of Massachusetts, have invented an Improvement in Holding Devices for Sole-Clamping Means, of which the following is a specification.

This invention relates to certain improvements in devices for holding a stack of cemented soles and taps pressed together, while the cement sets, and more particularly to improvements on the particular device for this purpose, described in my pending application #814,641.

In said prior device the arms of the U-shaped strap which engaged the upper clamping member were arranged to slide within the arms of the lower strap, and an independent clip was provided, which was connected to the ends of the lower strap and through which the arms of the upper strap were arranged to slide, the cam levers being pivoted in said clip and arranged in slots formed in the arms of the lower strap, in position to engage the arms of the upper strap.

This construction was found to be objectionable for several reasons. The straps could not be moved together to the extent desired, as the arms of the upper strap engaged the sole-holding board of the lower strap, in attempting to compress a small stack, provided the arms were made long enough to compress a large stack, thereby reducing its range of usefulness. Also, the holding surfaces of the cam dogs were not as long as desirable, and the cost of manufacture was found to be excessive.

The object of the present invention is to provide a form of holding device for the clamping members of the same general character as that of my said prior application, in which the arms of the upper strap will not be limited in their movement by the lower sole-engaging board, in which locking cam levers may be employed which are of the same width as the arms of the upper strap, and in which the construction, as a whole, is simplified, so that the cost of manufacture may be reduced.

I accomplish these objects by the means shown in the accompanying drawing, in which:

Figure 1 is a side elevation of a device embodying my invention.

Fig. 2 is an end elevation thereof, showing the parts in clamping position.

Figs. 3 and 4 are detail side and plan views of the clamping lever.

As shown in the drawing, the U-shaped strap *a*, which is designed to engage the lower clamping board *b* for the stack of soles, is provided with a pair of outwardly projecting ears *a'*, at the ends of its arms, providing a slot therebetween, in which the arms of the upper strap *c* are adapted to slide in close proximity to the sides of said ears, and also at their inner sides, to the outer sides of the arms of the lower strap *a*. A cam lever *d* is mounted between each pair of ears *a'*, on trunnions *e* supported thereby, the length of the cam faces thereof being approximately the same as the width of the upper strap arms *c*, said levers, also, being so arranged that, when the arms of the upper strap are slid downwardly, the action will be to throw the arms of the cam levers upwardly to unlocked position, as indicated in Fig. 3, so that the upper strap may be pressed downwardly without obstruction, but will be locked against upward movement by the downward swinging of the cam levers, which are normally held in position to lock by the gravity of their arms.

In practice, the soles are stacked on the bottom board *b*, the top board *f* is placed thereon, and the whole stack is then placed within the straps between the members of a press, as indicated in Fig. 1. The press members, on being forced together, force the clamping boards and strap members together to the desired extent and then, to avoid releasing the pressure to any appreciable extent, when the press members are separated, the cam-lever-arms are forced downward as far as possible by hand, springing the arms of the upper strap against the outer sides of the lower strap into strong frictional engagement therewith and preventing separation thereof, any tendency of the strap members, to separate, acting to cause the cam levers to swing downwardly still farther, thereby correspondingly increasing the force with which the arms are held together.

When the soles are removed from between the clamping boards, the stack is preferably first inverted, and then the cam levers are pressed down, unlocking the arms, so that the bottom board and strap member may be lifted from the stack.

With the above-described construction, the

surface provided for frictional engagement between the arms is, ordinarily, or except in the extreme positions of separation in which they may be locked together, greater than with said construction of my said prior application, the cam levers engage the upper arms throughout the entire width of the latter, thereby providing a stronger frictional engagement, while the range of adjustment of the arms is practically only limited by the length of the arms of the upper strap, the actual range being only slightly less than the length thereof.

The cost of manufacture of the present device is also much less than that of said prior device.

In the claims the terms "upper" and "lower" are used relatively, as it would be possible to use the device in an inverted position.

I claim:

1. A clamping device comprising a pair of members, one member having a pair of parallel arms formed with outer and inner clamping faces and parallel edges and the other member having a pair of outwardly projecting ears at each side thereof and a clamping face between each pair of ears, each arm being arranged in sliding engagement at its edges with the adjacent sides of one of said pairs of ears and its inner face with the corresponding outer face of the

other member, and a lever pivoted in each pair of ears, each having a cam-face at one end extending for approximately the width of the corresponding arm and arranged to be forced into clamping engagement with the outer face of such arm, to force the inner face thereof against the adjacent face of the other member.

2. A clamping device, comprising an upper and a lower member, each having a pair of oppositely extending, parallel arms, the arms of the upper member being arranged to overlap the arms of the lower member in sliding relation with the outer sides thereof, and the arms of the lower member each having a pair of ears projecting outwardly past the arms of the upper member, between which the arms of the latter slide, and by which they are guided, and a cam lever pivoted in the outer end portions of each pair of ears, in position to permit clamping movement of said members and be moved into locking engagement with the outer sides of the arms of the upper member to prevent separation of said members.

In testimony whereof, I have signed my name to this specification in the presence of two subscribing witnesses.

GEORGE E. BRITTAINE.
